United States Patent

Des. 236,019

Patented July 22, 1975

236,019

CROSS PENDANT OR THE LIKE

Robert K. Scott, Jacksonville, Fla., assignor to
Abba House, Inc., Jacksonville, Fla.

Original design application Nov. 8, 1972, Ser. No.
304,662, now Patent No. 233,362. Divided and this
application Aug. 2, 1974, Ser. No. 494,323

Term of patent 14 years

Int. Cl. D11—01
U.S. Cl. D45—16 B

FIG. 2

FIG. 3

FIG. 1 is a front elevational view of a cross pendant or the like showing my new design, portions of the neck chain being omitted for clarity of illustration;

FIG. 2 is a side elevational view thereof, the chain being shown in fragment; and

FIG. 3 is a detail sectional view of a part thereof on an enlarged scale and taken along line 3—3 of FIG. 1.

This is a division of application Ser. No. 304,662, filed Nov. 8, 1972, now Design Pat. 233,362, patented Oct. 22, 1974.

I claim:

The ornamental design for cross pendant or the like, substantially as shown.
